LOCK

Filed Aug. 27, 1921

UNITED STATES PATENT OFFICE.

LOUIS FRIEDMAN, OF NEW YORK, N. Y.

LOCK.

Application filed August 27, 1921. Serial No. 495,920.

To all whom it may concern:

Be it known that I, LOUIS FRIEDMAN, a citizen of the United States, and a resident of the city of New York, borough of Manhattan, in the county and State of New York, have invented a new and Improved Lock, of which the following is a full, clear, and exact description.

The present invention relates to new and useful improvements in lock structures, and it pertains more particularly to a lock especially adapted for use in connection with doors and the like.

It is one of the primary objects of the invention to provide a new and improved lock mechanism of such a structure as to prevent a forcing open of the door by springing the same relative to the jamb commonly known as "jimmying."

It is a further object of the invention to provide a new and novel combined manual and key-operated means for releasing the lock.

It is a further object of the invention to provide a lock which will automatically snap to locking position upon closing of the door.

It is a further object of the invention to provide a plurality of sliding latches adapted for interengagement with rigid dogs to effect a locking action.

It is a still further object of the invention to provide new and improved means for imparting parallel motion to the sliding latches upon releasing the locking mechanism.

With the above and other objects in view, reference is had to the accompanying drawings, in which—

40 Figure 1 is a vertical sectional view of a lock constructed in accordance with the present invention;

Fig. 2 is a horizontal sectional view thereof taken at right angles to Fig. 1;

45 Fig. 3 is a vertical sectional view taken on the line 3—3 of Fig. 1;

Fig. 4 is a similar view taken on the line 4—4 of Fig. 1;

50 Fig. 5 is a view similar to Fig. 4 showing the position of the several elements of the lock during the operation of the sliding latches by the rigid dogs;

Fig. 6 is a detail perspective view of one of the elements employed to impart parallel motion to the latch members.

Referring more particularly to the drawings, the reference character 10 designates the jamb, and 11 designates the door. The jamb is provided with a face or finishing plate 12, secured thereto by screws or the like 13, and rigidly carried by said finishing plate 12 are rigid dogs 14 and 15 arranged in spaced relation one to the other. These rigid dogs 14 and 15 are more clearly shown in Figs. 4 and 5, and the upper dog 14 has an arrow-like head 16, which structure provides two oppositely-disposed shoulders 17. The lower dog 15 is provided with one shoulder 18 and the dog 15 is so positioned with respect to the finishing plate 12 as to have its shoulder 18 positioned downwardly or upon the lower side of said dog.

The reference character 20 designates a housing and said housing has a removable rear plate 21 secured to the housing proper by means of suitable fastenings in the form of screws or bolts 22. This housing is adapted to be secured to the door 11 by screws or the like 23, which pass preferably entirely through said housing, as more clearly shown in Fig. 2. Extending transversely of the housing on the interior thereof are guides 24, the preferred form of arrangement being one of said guides adjacent each end of the housing 20. Slidably mounted upon the guide 24, is a latch 25, said latch 25 being arranged in the lower portion of the housing 20 and having an upstanding section or shoulder 26. Mounted above the sliding latch 25 are two sliding latches 27 and 28. The sliding latch 25 is notched as at 29 to engage the ratchet lug 15 in a manner to be hereinafter more specifically described and the sliding latches 27 and 28 are notched as at 30 and 31, respectively to engage the opposite sides of the upper or double rigid dog 15.

Carried by each of the guides 24 and interposed between the lower sliding latch 25 and the bottom wall of the housing 20, is a coil spring 32, and interposed between the upper face of the upper sliding latch 27 and the upper wall of the housing and surrounding the upper end of each of the guides 24, is a coil spring 33. The coil springs 32 tend to force the lower sliding latch 25 upwardly a sufficient distance for its enlarged portion 26 to engage the lower edge of the sliding latch 28, and the coil

springs 33 tend to force the upper sliding latch 27 downwardly until it engages the lower sliding latch 28.

- 5 Mounted in the front wall of the housing 20 in such a manner as to be freely rotatable therein, is an operating knob 35, and said operating knob is provided with an inwardly projecting squared shaft 36. Mounted upon the squared shaft 10 36 upon the interior of the lock housing, is a cam member 37, and said cam member 37 is adapted to occupy a position between the upper sliding latches 27 and 28, said latches being cut out as indicated by the reference 15 character 39 to receive said cam. The reference character 37' designates a cam member similar to the cam member 37 and will be hereinafter more fully referred to.
- By this construction it is apparent that as 20 the operating knob 35 is rotated the cam member 37 will likewise be rotated between the sliding latch members 27 and 28, and will tend to spread them against the action of the springs 33 in one direction and the 25 springs 32 in the other direction in a manner to be hereinafter more fully described. The cam member 37' has an extension 39, and said extension 39 projects into a lock mechanism 40 of any desired key-operated type.
- 30 The reference character 42 designates a lever of which there are two, and each of said levers has a circular opening 43 adapted to receive the squared shaft 36. Each of these levers is provided upon one end with 35 a right-angular portion 44, and upon its other end with a vertical extension 45 terminating in a right-angular extension 46. These levers 42 are positioned to the front of the sliding latches and the right-angular 40 extension 46 of one of the levers engages the upper face of the upper sliding latch 27, while the right-angular extension 46 of the other lever engages the lower face of the sliding latch 28. The right-angular extension 45 of that lever whose right-angular extension 46 engages the upper edge of the sliding latch 27, engages the upper face of the sliding latch 28, and the right-angular extension 44 of that lever 42 whose right- 45 angular extension 46 engages the lower edge of the sliding latch 28, engages the under edge of the sliding latch member 27. By this construction it is apparent that as the squared shaft 36 is rotated by means of the 50 operating knob 35, the two latch members 27 and 28 will be spread and their movements will be parallel to each other since as the upper sliding latch member 27 is lifted by means of the cam member 37, it exerts an 55 upward force on the right-angular extension 46 which engages its upper face, and the opposite end of the lever which carries the right-angular extension 46 will engage the lower sliding latch member 28 and force it 60 downwardly. This action also takes place

through the medium of the other lever 42 in the following manner: As the lower sliding latch member 28 is forced downwardly, the opposite end of the lever 42 whose right-angular portion 46 engages the under face 70 of the sliding latch 28, will exert an upward force upon the upper latch member 27, thus causing the two sliding latch members 27 and 28 to move in parallelism to each other.

By reason of the enlarged portion 26 of 75 the sliding latch member 25 engaging the lower edge of the sliding latch member 28, it will be obvious that upon operation of the cam member 37, and when the lower latch member 28 is depressed, the sliding latch member 25 will likewise be depressed against the action of the coil springs 32.

The operation of the device is as follows:

Assuming that the door 11 is in open position, upon closing said door, the rigid dogs 14 and 15 will enter openings 50 and 51 respectively in the lock housing, and the upper dog 14 owing to its arrowhead construction will spread the sliding latch members 27 and 28 and pass between them, as shown 80 in Fig. 5. Simultaneously with this operation, the rigid dog 15 engages the lower sliding latch member 25 and force the same downwardly against the action of the coil springs 32. As the door moves to completely 85 closed position, the sliding latch members under the influence of the springs 32 and 33 will engage their respective shoulders of the rigid dogs 14 and 15, and will maintain the door in locked and closed position.

When it is desired to open the door from the inside, the operating member 35 is rotated by hand and the cam member 37 serves to spread the sliding latch members 27 and 28 to a position where they will clear the shoulders 17 and the dog 14. Owing to the engagement of the lower sliding latch member 28 with the enlarged portion 26 of the sliding latch member 25, the sliding latch member 25 upon movement of the sliding latch member 28 will be moved to a position where it will disengage the shoulder 18 of the rigid dog 15.

This same operation may be carried out from the outside of a door by insertion of 115 a key in the lock 40 in the ordinary manner.

I claim:

1. A lock comprising a housing, a plurality of sliding latches in said housing, a plurality of parallel rigid dogs, said dogs being adapted to pass between the sliding latches, and one of said dogs being engaged on opposite sides by said sliding latches, the other dog being engaged on one side by one of said sliding latches, and resilient means for maintaining said sliding latches and said dogs in engagement with one another.

2. A lock comprising a housing, a plurality of parallel sliding latches mounted in the housing, a plurality of rigid dogs ex- 130

- ternal of the housing and adapted to pass thereto and into engagement with said sliding latches, resilient means for maintaining said sliding latches in engagement with said dogs, means for spreading said sliding latches to permit of their disengagement with the dogs, and means for imparting parallel movement to the sliding latches upon operation of the spreading means.
- 10 3. A lock comprising a housing, a plurality of parallel sliding latches mounted in said housing, a plurality of rigid dogs adapted to enter said housing and have interengagement with said sliding latches, shoulders carried by said dogs adapted for engagement with said sliding latches to prevent relative movement of the dogs and housing, and means for operating said sliding latches to disengage them from the dogs
- 15 to permit of relative movement between the dogs and the housing, and a rocking lever operated by the latch operating means and engaging said parallel latches to give parallel movement thereto.
4. A lock comprising a housing, transversely extending guide rods mounted in said housing, a plurality of sliding latches mounted on said guide rods, two of said latches being arranged to constitute a pair and one latch separate from said pair, and means for spreading the latches of said pair and said single latch simultaneously.
5. In a lock, a housing, a plurality of sliding latches, said latches being arranged to constitute a pair and a single latch spaced with respect thereto, means for spreading the pair of latches and simultaneously operating the third latch, and means for imparting a parallel movement to the latches constituting the pair, said means comprising a plurality of levers interposed with respect to the latches constituting the pair and engaging the opposite ends thereof.

LOUIS FRIEDMAN.
